(21) Appl. No.: **35/507,681**

(22) Filed: **Nov. 7, 2018**

(57)

CLAIM

(80) **Hague Agreement Data**

The ornamental design for a water meter, as shown and described.

Int. Filing Date: **Nov. 7, 2018**

DESCRIPTION

Int. Reg. No.: **DM/203703**

1. Water meter

Int. Reg. Date: **Nov. 7, 2018**

1.1 is a front perspective view.

Int. Reg. Pub. Date: **Nov. 8, 2019**

1.2 is a front view perspective shown in an alternate position.

(51) LOC (12) Cl. **10-04**

1.3 is a top view.

(52) U.S. Cl.

1.4 is a top view shown in an alternate position.

USPC **D10/99**

1.5 is a bottom view.

(58) **Field of Classification Search**

1.6 is a left side view.

USPC D10/99, 96

1.7 is a right side view.

See application file for complete search history.

1.8 is a front view.

(56) **References Cited**

1.9 is a rear view.
